CLAIM

The ornamental design for a railroad boxcar lading anchor, as shown and described.

DESCRIPTION

FIG. 1 is a front elevational view of the railroad boxcar lading anchor of the invention;

FIG. 2 is a back elevational view of the railroad boxcar lading anchor of FIG. 1;

FIG. 3 is a left end elevational view of the railroad boxcar lading anchor of FIG. 1;

FIG. 4 is a right end elevational view of the railroad boxcar lading anchor of FIG. 1;

FIG. 5 is a top plan view of the railroad boxcar lading anchor of FIG. 1; and,

FIG. 6 is a bottom view of the railroad boxcar lading anchor of FIG. 1.
